UNITED STATES PATENT OFFICE.

JOHN WOLF, JR., AND JACOB BLOCH, OF CINCINNATI, OHIO.

CLOTH-CUTTING MACHINE.

SPECIFICATION forming part of Letters Patent No. 505,689, dated September 26, 1893.

Application filed November 10, 1892. Serial No. 451,507. (No model.)

To all whom it may concern:

Be it known that we, JOHN WOLF, Jr., and JACOB BLOCH, citizens of the United States, residing at Cincinnati, in the county of Hamilton and State of Ohio, have invented certain new and useful Improvements in Cloth-Cutting Machines; and we do hereby declare the following to be a full, clear, and exact description of the invention, such as will enable others skilled in the art to which it appertains to make and use the same.

This invention relates to machines or instruments for cutting textile fabrics and other materials, but more particularly to a class of machines used in cutting out cloth suits and other clothing. Machines of this character have heretofore been devised, in some of which it has been proposed to employ a rotary cutter journaled in a frame mounted upon a standard that rises from a foot-plate and supports a rotary air or steam-actuated motor and driving gearing for imparting motion to the cutter, so that the latter may cut its way through the cloth as the machine is moved forward by the hand of the operator with the foot-plate underneath the cloth. It has also been proposed to employ electric motors for imparting motion to a reciprocating knife, and also to drive a rotary cutter by means of belts and pulleys connecting the knife-arbor with the motor-shaft or with a driven shaft connected by jointed arms and intermediate driving gearing with a stationary source of power. The latter class of machines is subject to objection for the reason that only a limited movement is permitted and the machine and its actuating mechanism are more or less complex, cumbersome and expensive, making the initial cost of the machine considerable and increasing the cost of maintenance by frequent renewal of parts of the complex structure. The machines in which an air or steam motor is employed are also objectionable because of their bulk and unwieldiness and their motion is irregular and thumping, rendering it difficult to control the movements of the machine so as to cut the cloth according to the desired pattern. The electrically operated machines carrying reciprocating knives are also objectionable for similar reasons; such machines being top-heavy and unsteady in operation, producing

a tremulous or vibratory movement, rendering them liable to swing around or jump about the table, and by reason of their top-heaviness they are easily tipped or overturned so as to cut and damage the goods. And wherever belts and pulleys are employed it is difficult to insure a regular and smooth cut, owing to the liability of the belts to stretch, slip and break, and also to cause the machine to become clogged by small particles of the cut fabric adhering to the belts.

The objects of our invention are to overcome these several difficulties and to provide a comparatively light, simple, compact, inexpensive and smoothly running machine, which may be moved freely about the table in any desired direction, and readily lifted from table to table, and which in operation will produce a smooth easy running cut, and may be easily controlled and made to follow the contour of the pattern or the sinuous lines or marks upon the cloth without liability to clogging or miscutting by reason of any irregular or tremulous motion.

With these and other objects in view the invention consists in certain improved features of construction and combinations of parts all as will be hereinafter described and particularly pointed out in the claims at the end of this description.

Referring by letters of reference to the accompanying drawings which form a part of this specification, Figure 1, represents a side elevation, on a reduced scale, of a cloth cutting machine embodying our invention. Fig. 2 is a front elevation, partly in section; Fig. 3 a side elevation and Fig. 4 a plan of the machine. Fig. 5 is a detail horizontal section taken on line 5-5 of Fig. 3. Fig. 6 is a longitudinal sectional elevation illustrating a modification of the foot-plate, and Fig. 7 is a detail.

Similar letters of reference are used to denote similar parts in each of the several views.

A denotes a foot-plate from which rises the standard B, which may be formed integrally therewith or secured thereto in any proper manner. The foot-plate A is preferably rectangular in form and provided with a plain upper surface or top, and the standard preferably rises therefrom at the intersection of two horizontal lines crossing each other through

the longitudinal and transverse center of the plate, but at one side of such longitudinal line and with its front edge in advance of such transverse line, so as to place the standard 5 mainly within the space comprising a quadrant of the plate, and thus provide a plain surface of less extent upon one side and in front of the cutter than at the opposite side and in rear of the standard, so as to afford an 10 extended and even surface on that side of the foot-plate which is beneath the main body of the cloth; the cut portion being turned aside by the standard as the cutter advances. The standard B, which supports the rotary cutter 15 and its actuating mechanism, may be formed with a plain inner face and front curved and beveled edge b, while its outer face or side is slightly inclined toward the rear, and it has upon its rear edge an inwardly projecting lip or flange b' (Fig. 7) which overlaps the rear edge of the rotary cutter C, as indicated in dotted lines in Fig. 5, so as to protect the cutter and prevent the hand of the operator or the cloth from coming in contact therewith when the machine is moved in a backward direction. The standard B may also be formed or provided with a laterally projecting split portion or clamp B' at its upper end, having a vertical opening therethrough to receive the post D. The post D supports the framing which overhangs the foot-plate at one side and has mounted thereon the electric motor M, and the mechanism connected therewith for imparting motion to the rotary 30 knife or cutter. Said post is adapted to slide vertically through the opening in the clamp B' when the binding screw b² is loosened to permit the bifurcated portion of the clamp to be spread apart sufficiently to release the post. This adjustment may be secured by means of a screw threaded rod E upon which is fitted an internally screw threaded bevel-wheel F fitting within and resting upon the base of a socket or recess b³ formed in the clamp B', and meshing with a similar bevel-wheel F' fixed on a stud or spindle f which has its bearings in one of the arms of the clamp B', and is provided with a square or polygonal end f' to receive a wrench for the 40 purpose of rotating the stud. The upper end of the rod E is secured to a cross-piece of the main frame which is adapted to rest thereon. By this means, when the bevel-wheel F' is rotated a rotary movement will be imparted to the bevel-wheel F, and as the latter is screw threaded upon the rod E the rod will move up or down and raise or lower the superstructure, together with the rotary knife and its actuating mechanism; the clamp B' being 50 loosened to permit the post D to rise or fall by loosening the binding screw b². In this manner a very nice adjustment of the rotary knife may be accomplished as its cutting edge becomes worn, and the adjustment may be 55 made with very little expenditure of time, by merely loosening the screw b² and giving the stud f the desired number of turns, and again

tightening the screw so as to clamp the post and rod firmly in the desired position upon the standard.

G, denotes a cloth-lifting plate or shoe having a rectangular or other suitable opening therethrough corresponding with the angular or other shape of the foot-plate which it is adapted to receive, and about which it is loosely fitted so as to permit a free vertical movement of either the foot-plate or the cloth-lifting plate, within certain limits, without disconnecting the parts; the foot-plate being confined within the opening of the surrounding shoe so as to compel the latter to move in a horizontal plane in harmony with the movements of the foot-plate. The inner edges of the cloth-lifting plate or shoe are normally flush with the adjacent edges of the foot-plate 85 so as to provide a free and unobstructed surface over which the cloth may pass or slide as the foot-plate and shoe are moved in the desired direction underneath the cloth. The sides or wings g, g, of the shoe are inclined 90 outwardly and downwardly from the foot-plate, the inclination thereof being preferably rather steep, while its ends, or heel and toe g', g², are gently inclined downwardly, and rearwardly and forwardly, respectively, from 95 the foot-plate; the toe g² being lengthened so as to provide a very gently sloping surface in advance of the cutter.

The cutter C, may be secured upon an arbor c, which has its bearings in a sleeve or 100 casing H projecting from the depending portion of the casing I secured at one side of the frame; the outer end of the sleeve being secured to a depending arm K of the frame. The sleeve H is provided with a hinged cover 105 h for the introduction of lubricating material. The arbor c passes through an opening in the cutter and through the sleeve H into the casing I, and is secured by a nut on its inner screw-threaded end. Within the casing it 110 carries a pinion c' which meshes with a driven spur-wheel L which is fixed upon an arbor or spindle journaled in suitable bearings attached to the casing I. An oil cup l, may be provided at the inside of the casing; said cup 115 having a suitable opening and cover to permit the introduction of oil or other lubricating material. By housing the gearing which imparts motion to the cutter within the inclosing casing, as shown, the bearings may be 120 freely lubricated, while the gear wheels are protected and prevented from becoming clogged by small particles of the cut fabric and lint which might otherwise adhere thereto, and the cloth which is being cut is also 125 prevented from being soiled by the lubricant or injured by contact with the gearing.

The motor M, may be of any approved construction, though preferably of the form shown, which illustrates a well known type of motor, and inasmuch as the construction of the same forms no part of our present invention, a specific description thereof is not deemed necessary herein. The motor M may

be mounted as shown upon the framing of the machine over the rotary cutter C, at the side of the frame opposite the portion overhanging the foot-plate and only slightly above the cutter, so as to leave room for the intermediate driving gearing, thus causing the center of gravity to fall within the base about a point on a perpendicular line cutting the rear edge of the knife. As will be seen, the armature-shaft of the motor and the shafts of the rotary cutter and grinding disks extend laterally with the framing of the machine at one side of the standard, and at said side is arranged the driving gearing for imparting motion to said cutter and disks, and the motor is so mounted as to throw a preponderance of its weight on the side of the standard opposite said shafts, so as to counterbalance the weight upon the standard; whereby the several parts are assembled in compact form, and the center of gravity is lowered, so as to balance and steady the movements of the machine and avoid any tendency thereof to topple over in operation, while a positive motion is imparted from the armature-shaft of the motor to the cutter.

A pinion n is fixed upon the end of the armature shaft N, within the casing I and meshes with the gear wheel L. By this means, when the motor is in motion a rotary movement will be imparted to the cutter C through the intermediate gearing c' , L, n , and by reason of the compact arrangement and positive driving-gearing the machine will run smoothly and may be easily controlled, without liability to tip over or be jerked around the table by any sudden thrust, which defects are incident to the use of a reciprocating knife and the irregular motion due to the use of belts and pulleys and air and steam motors. The armature shaft N may have its bearings in suitable boxes n' , n'' , one of which is secured to the inner side of the casing I and the other to a cross-piece O attached to the field magnets as shown in Fig. 3.

In cutting different kinds of cloth the edge of the cutter wears more or less rapidly, according to the character of the cloth, and to retain a sharp edge upon the cutter it is necessary to provide a sharpening device by which the cutter may be sharpened while the machine is in operation.

It has heretofore been proposed to provide sharpening devices in which a grinding wheel or wheels are held normally in contact with the blade, and provision has also been made for adjusting the sharpening wheel in relation to the cutter, but in order to secure such adjustment it is necessary to stop the machine and make the adjustment by means of a wrench or screw driver, thus necessitating considerable loss of time. To overcome this objection and at the same time to provide a simple and efficient sharpening device, we have devised means whereby an instantaneous adjustment may be accomplished by simply turning a thumb-nut, so that during the operation of cut-

ting the operator may readily adjust the grinding disk or disks in relation to the blade, so as to grind more or less rapidly according to the rapidity with which the cutting edge is worn by reason of the character of the cloth which is being cut. The mechanism for this purpose may be constructed as follows:—P denotes a sleeve projecting in an oblique direction to the axis of the cutter from a hinged bracket-arm Q, one end of which is fitted to turn upon a stud or pin q (Fig. 3) projecting from the inner side of the casing I, and its opposite free end is adjustably secured to the casing by a set-screw or tap-bolt q' which passes through a curved slot q'' in the arm into a threaded opening therefor in the casing. P' denotes a shaft or spindle extending through the sleeve P and through a curved slot in the side of the casing I, and is provided with a pinion p which meshes with a bevel-wheel L' secured to or formed upon the inner side of the gear wheel L; the stud upon which the bracket-arm Q is pivoted being arranged concentric with the axis of the gear wheel L' so that the free end of the bracket may be raised and lowered without disengaging the pinion p . The shaft P' may carry at its outer end a grinding wheel or preferably a pair of grinding wheels or disks R, R, which straddle the rotary cutter C so that the inner sides thereof bear upon opposite sides of the cutter. The disks R are keyed upon the shaft so as to rotate therewith, but are free to slide lengthwise thereof, being confined between a pair of depending arms or bars S, S, fitted on the shaft P', and having their upper ends pivoted to an arm t projecting horizontally from the upright portion of an angle-bar T, which may be sleeved fast upon the inner end of the sleeve P or secured thereto in any proper manner. S' denotes a tension rod which passes loosely through openings in the arms S, S, and is provided with a thumb-nut s at one end and a head or nut at the other so as to permit a limited movement of the bars S, S, toward or from each other; the thumb-nut s being supported in position to be readily grasped by the hand of the operator for the purpose of turning the same and thereby increasing or decreasing the pressure of the grinding wheels upon the cutter by causing the wheels to approach or recede from each other. A spring s' is interposed between the nut s and the outer arm S so as to permit said arm to yield when forced outwardly by any abnormal pressure upon the disk or disks tending to force them apart, and a spring r is placed between the hubs of the disks so as to hold them normally apart and resist any force tending to cause them to approach each other. By these means, the grinding wheels are held in yielding engagement with the sides of the cutter and the disks are forced apart by spring pressure so as to maintain a fixed position in respect to each other and exert a greater or less pressure upon the cutter, as may be desired, while permitting an easy adjustment thereof.

when the machine is in operation. The cutter will thus be ground true although it or the wheel may not be true, as is generally the case, it being difficult to construct or hang the disks and cutter perfectly true.

U denotes an electric lamp which may be of any suitable or preferred construction and is connected in circuit with the source of electric supply to the motor, so that when current is supplied to the motor the lamp will also be supplied. The lamp is adjustably secured with relation to the cutter so as to permit the light to be thrown upon the work in such manner as to enable the operator to readily guide and control the movements of the machine, for the purpose of causing the cutter to follow the contour of the pattern or the sinuous lines or marks upon the cloth. The connection may be made by any suitable clamping device 15 which will permit a vertical and lateral adjustment of the lamp, but we preferably employ for this purpose a universal or ball-and-socket joint as shown, which may consist of a split or divided clamp V provided with 20 cavities on the inner faces of the free ends of the split parts to receive a knob or rounded protuberance u, projecting from the lamp socket as shown; such bifurcated portion being provided with a binding screw v, by which the 25 parts may be compressed so as to bind the knob in the socket formed by the aforesaid concavities and hold the lamp in any desired 30 position. This construction has the advantage of permitting a very nice adjustment of the lamp, so as to prevent casting shadows across the line of movement of the cutter or the marks upon the cloth, and adapts the light to be thrown to the best advantage to meet varying conditions and requirements in 35 cutting different kinds of cloth, whereby the operator may cause the knife to follow the sinuous lines or marks without liability to turn toward either side of the mark and thereby damage the cloth. The circuit wires W, 40 connecting with the motor M, may lead therefrom to a stationary source of electric supply over any suitable support upon the ceiling or other elevated portion of the building, as indicated in Fig. 1.

50 To provide the necessary length of wire to enable the operator to move the machine to any part of a large room, and from table to table, and at the same time prevent entanglement of or interference with the workman by 55 a superfluous length of wire, we provide an automatic take-up device, by which the slack or superfluous length of wire is automatically taken up and paid out in such length as may be desired in moving the machine from table to table or over a long table. This device may consist of a cord X secured at one end to the flexible wires W and extending therefrom over a pulley or pulleys x, x', or other suitable elevated support, and provided at its 60 free end with a weight x², by which the cord will be kept taut. By this means any superfluity in the circuit wires will be automatically taken up and sustained in an elevated position and out of the way, but may be easily drawn out following the movement of the machine when more wire is needed.

The frame-bar K is formed with a rearward extension k, which terminates in a notched segment k', to which a handle K' is pivoted as at k², so as to permit the handle to swing both laterally and vertically for the purpose of changing its position; a detent or tooth k³ upon the shank of the handle being adapted to engage either one of three (more or less) notches in the upper face of the segment, as shown in Fig. 4, so as to retain the handle in either of three positions, that is, in a position inclined either to the right or left of the machine and oblique to the axis of the cutter, or in a position parallel with the cutting 85 blade.

In Fig. 6 is shown a modification of the foot-plate wherein a dip or concavity a, is formed by a gentle incline from the front edge of the standard to a point in rear thereof, from which point the slope is gently upward to the surface of the plate. This depression provides a clearance in rear of the cutter and permits the cloth to dip as the foot-plate moves thereunder so as to facilitate the cutting and adapt the instrument to more readily turn corners or acute angles in following the marks upon the cloth.

While we have shown and preferably use a grinding disk for each side of the cutter, it is obvious that one of said disks might be dispensed with, in which case the spring for holding the disks apart might be interposed between the disk and arm, or a collar on the shaft on which the disk is mounted, so as to force the disk outward against the opposing pressure of the spring upon the tension rod. The sides of the disks facing the cutter may be plain or cored out as shown so as to leave a rounded peripheral projection only to make contact with the edge of the cutter. The foot-plate is also preferably mounted on rollers which may be placed at the four corners thereof so as to prevent friction and facilitate the movement of the machine. A switch of any suitable construction as shown at X² may be employed for turning on and cutting off the current. It is also obvious that while an electric motor is preferable any suitable motor may be employed in connection with a foot-plate and standard, or cloth-lifting plate and sharpening devices such as we have described. Hence we do not desire to be limited to the exact construction and arrangement of parts shown and described.

Having thus fully described our invention, what we claim as new, and desire to secure by Letters Patent, is—

1. A cloth cutting machine comprising the foot-plate having a standard rising therefrom, the cloth-lifting plate fitting loosely around said foot-plate, a motor mounted on said standard, a rotary cutter journaled below said motor, and means arranged to impart motion

from the motor to the cutter, substantially as described.

2. In a cloth cutting machine, the combination with the foot-plate and cutting mechanism supported thereon, of the gravitating cloth-lifting plate fitting loosely about said foot-plate flush with the upper surface thereof and having its sides and ends inclined outwardly and downwardly therefrom, substantially as described.

3. In a cloth cutting machine, the combination with the foot-plate having the standard rising therefrom and supporting the cutting mechanism, of the cloth-lifting plate surrounding said foot-plate flush with the upper surface thereof and having its sides and ends inclined downwardly and outwardly from such surface, substantially as described.

4. In a cloth cutting machine, the combination with the foot-plate having the standard thereon, of the rotary cutter journaled at one side of said standard, the rotary electric motor mounted over said cutter so as to throw a preponderance of its weight on one side of the standard; the cutter-shaft, the armature-shaft of the motor, and the framing of the machine being extended laterally at the opposite side of the standard so as to overhang the foot-plate and counterbalance the weight; a pinion on each of said shafts, and an intermediate gear-wheel journaled in said framing and meshing with said pinions, whereby the several parts of the machine are assembled in compact form and the weight on opposite sides of the standard is counterbalanced while the center of gravity is lowered, so as to balance and steady the movements of the machine and impart a positive motion to the cutter from the armature-shaft of the motor, substantially as described.

5. In a cloth cutting machine, the combination with the foot-plate having the standard thereon, of the rotary cutter journaled in a frame supported by said standard, a rotary motor mounted over the cutter, gearing arranged to impart motion from the motor to the cutter and a casing inclosing said gearing, substantially as described.

6. A cloth cutting machine comprising the foot-plate having the standard rising therefrom, the frame supported by said standard so as to overhang the foot-plate at one side, the casing supported above said foot-plate at said side thereof, an arbor extending from said casing and supporting a rotary cutter adjacent to said standard, a rotary electric motor mounted over said cutter with its shaft extending laterally to said casing, and a spur-gearing inclosed in said casing and adapted to transmit motion from the motor to the cutter, substantially as described.

7. In a cloth cutting machine the foot-plate having a plain upper surface with a standard rising therefrom and supporting a rotary cutter, and mechanism for rotating the cutter, in combination with the cloth-lifting plate fitting loosely about said foot-plate with its in-

ner edges normally flush with the upper surface thereof and sloping outwardly therefrom; said cloth-lifting plate being free to rise and fall independently of the foot-plate, substantially as described.

8. In a cloth cutting machine, the rectangular foot-plate having a plain top with a standard rising therefrom and supporting a rotary cutter and its actuating mechanism, in combination with the cloth-lifting plate having the rectangular opening to receive said foot-plate and inclined outwardly and downwardly therefrom at its sides and ends; the inclined portion of the cloth-lifting plate at one end being lengthened so as to form an extended gently sloping surface in advance of the cutter, substantially as described.

9. In a cloth cutting-machine, the foot-plate mounted on rollers and having a standard rising therefrom and supporting a rotary cutter and an actuating mechanism, in combination with the gravitating cloth-lifting plate fitting loosely about said foot-plate so as to permit free vertical movement thereof; said cloth-lifting plate having sloping sides and ends the inner edges of which are normally flush with the upper adjacent edges of the foot-plate, substantially as described.

10. The combination with the foot-plate, of the standard, the post adjustably secured to said standard, the motor mounted upon said post, the rotary cutter journaled in a depending portion of the motor-supporting frame and in gear with said motor, an elevating device for raising and lowering the post, and means for securing the parts in the desired position, substantially as described.

11. The combination with the foot-plate, of the standard, the post adjustably secured to said standard, the motor mounted upon said post, the rotary cutter journaled in a depending portion of the motor-supporting frame and in gear with said motor, and an elevating device for raising and lowering the post, comprising a screw-threaded rod depending from the main frame, a bevel-wheel screwed on said rod, a similar bevel-wheel meshing therewith fixed on a rotatable stud or arbor, and a clamp adapted to release or secure the rod against rotation, substantially as described.

12. In combination with the cutter and its actuating mechanism, the notched segment, and the vertically and laterally swinging handle provided with a detent for engaging the notches of the segment, substantially as described.

13. In combination with the rotary cutter, the grinding disks supported obliquely to the axis thereof, a tension device for holding the disks in yielding engagement with opposite sides of the cutter, and means for adjusting said device so as to vary the pressure upon the cutter at will, substantially as described.

14. In combination with the rotary cutter, the swinging bracket-arm and means for securing the same in the desired position, the shaft projecting obliquely from said arm, the

grinding disks keyed on said shaft and engaging opposite sides of the cutter, the spring for separating said disks, a tension device for holding the disks in yielding engagement with the cutter, and means for varying the tension, substantially as described.

15. In combination with the rotary cutter, the shaft extending obliquely to the axis thereof, the radially adjustable support for said shaft, a pair of grinding disks placed on said shaft so as to rotate therewith in contact with opposite sides of the cutter, means for adjusting the disks toward or from each other and sustaining them in yielding contact with the cutter, and a motor geared to said shaft and cutter so as to rotate the same, substantially as described.

16. In combination with the rotary cutter, the shaft extending obliquely to the axis thereof, the radially adjustable support for said shaft, a pair of grinding disks placed on said shaft so as to rotate therewith in contact with opposite sides of the cutter, a spring interposed between said disks and tending to force them apart, means for adjusting the disks toward or from each other and sustaining them in the adjusted position in yielding contact with the cutter, and means for rotating the disks and cutter, substantially as described.

17. In combination with the rotary cutter,

the shaft extending obliquely to the axis thereof, the hanging bars pivoted at one end and having their opposite ends loosely fitted on said shaft, the rod connecting said bars, the adjusting nut on said rod, the spring interposed between said nut and one of said bars, the grinding disks mounted on said shaft between said bars so as to rotate with the shaft in contact with opposite sides of the cutter, and the spring tending to force the disks apart, substantially as described.

18. In combination with the foot-plate having a plain top, the standard mounted thereon near one side and end, the frame adjustably secured to said standard so as to overhang the side of the foot-plate opposite the standard, the rotary cutter journaled in a depending portion of the frame, the rotary electric motor mounted at one side of the frame centrally above the cutter, a casing secured at the opposite side of the frame, and a train of spur-gearing housed in said casing and adapted to impart motion from the motor to the cutter, substantially as described.

In testimony whereof we affix our signatures in presence of two witnesses.

Corrections in Letters Patent No. 505,689.

It is hereby certified that in Letters Patent No. 505,689, granted September 26, 1893, upon the application of John Wolf, Jr., and Jacob Bloch, of Cincinnati, Ohio, for an improvement in "Cloth-Cutting Machines," errors appear in the printed specification requiring the following corrections: In line 83, page 1, the words *figures and* should be inserted before the word "letters"; line 88, page 5, the word "an" should read *its*; and that the Letters Patent should be read with these corrections therein that the same may conform to the record of the case in the Patent Office.

Signed, countersigned, and sealed this 3d day of October, A. D. 1893.

[SEAL]

WM. H. SIMS,

First Assistant Secretary of the Interior.

Countersigned:

S. T. FISHER,

Acting Commissioner of Patents.
